US0D1023126S

(12) **United States Design Patent** (10) **Patent No.:** **US D1,023,126 S**
(45) **Date of Patent:** **** Apr. 16, 2024**

(54) **GLASSES FRAMES**

(71) Applicant: **PAIR EYEWEAR, INC.**, New York, NY (US)

(72) Inventors: **Nathan Kondamuri**, Brooklyn, NY (US); **Sophia Edelstein**, Brooklyn, NY (US); **Lee Zaro**, Rancho Palos Verdes, CA (US)

(73) Assignee: **PAIR EYEWEAR, INC.**, New York, NY (US)

(**) Term: **15 Years**

(21) Appl. No.: **29/877,690**

(22) Filed: **Jun. 9, 2023**

Related U.S. Application Data

(63) Continuation of application No. 29/775,188, filed on Mar. 22, 2021.

(51) **LOC (14) Cl.** **16-06**
